Primary Examiner — Robin V Webster*Assistant Examiner* — Keith J Wilson(74) *Attorney, Agent, or Firm* — Stetina Brunda Garred and Brucker(57) **CLAIM**

The ornamental design for a propelled scooter, as shown and described.

DESCRIPTION

FIG. 1 is a front perspective view of the propelled scooter of the present invention showing our new design;

FIG. 2 is a rear perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front view thereof; and,

FIG. 8 is a rear view thereof.

The broken lines in the figures depict environmental structure and do not form any part of the claimed design.

1 Claim, 6 Drawing Sheets(56)
